FISHED RAIL JOINT

Norbert Vryens, Brussels, Belgium

Application May 20, 1932, Serial No. 612,574
In Belgium June 22, 1931

2 Claims. (Cl. 238—259)

The fished rail joint according to the present invention has for its object the taking up of the play which is produced between the fish-plate bearing surfaces near the ends of the joined 5 rails and the central portions of the fish-plates.

It should be noted at the beginning that in the joints of the prior art the fish-plate bearing surfaces of the rails, which receive practically all of the wear, are of a length of only several 10 centimeters. In effect, during the course of service and due to the repeated shocks of the passage of loads over the joints of the rails, the ends thereof are subjected to slight repeated bendings, which create an appreciable wear on the fish-plate bearing surfaces adjacent the ends 15 of the rails and at the central portion of the fish-plates, whereas the other portions of the fish-plate bearing surface formed on the rails and other portions of the fish-plates are subjected to very little wear.

To provide for the efficient taking up of clearance or loosening of the joints produced by the above-described wear, it is important that the clamping system satisfy, among other conditions, 20 the following:

In view of the considerable importance of the wear on the fish-plate bearing surfaces adjacent the ends of the rails compared to that of other parts of said bearing surfaces, it is necessary, in 25 order that the taking up of play between the fish-plate and fish-plate bearing surfaces on the rail be possible, that the central part of the fish-plate rest solely on the bearing surface provided on the inclined portions of the head and foot of 30 the rail and that a sufficient free space be left between the web of the rail and the fish-plate to permit further movement of the central portion 35 of the fish-plate toward the web of the rails.

Another condition to be realized at the same 40 time as the above is: In order that movement of the central portion of the fish-plate toward the rail be possible when the first condition is accomplished, it is essential that parts of the fish-plate other than the central portion, which 45 are also called elastic arms, do not oppose this movement. For this result, it is necessary that parts of the fish-plate other than the central portion be neither in contact with the fish-plate bearing surface, nor with the web of the rail.

The third condition to be complied with, together with the first two, is: In order that the 50 system be relatively efficient, the wear produced on the fish-plates and fish-plate bearing surfaces adjacent the ends of the rails must be taken up automatically in proportion to its formation. In

effect, in the case of the contrary, the slight initial wear produced will cause repeated shocks of the load passing over the joint and will result in a rapid increase of the initial wear. Consequently, for the automatic taking up of the play 5 to be possible, it is necessary when tightening the fish-bolts that an elastic tension be created in the fish-plate, which will tend to constantly move the central portion of the fish-plates toward the web of the joined rails. 10

The present invention complies with this condition, due to the fact that the fish-bolts are positioned near the middle of the portions of the fish-plates which are not in contact with the rails. In this condition, the tightening of the 15 fish-bolts has the effect of giving the elastic arms of the fish-plate a curvature, the convexity of which is directed toward the web of the rail. The elastic tension created in the portion of the fish-plate under the bending effect has a tendency 20 to urge the central portion of the fish-plate toward the rails and, consequently, will immediately take up any play between the fish-plate and the fish-plate bearing surface on the rails adjacent the ends thereof as it is produced. 25

The accompanying drawing shows by way of example, without in any way limiting the invention, several different constructions according to the invention. The invention covers the various original features comprised in the arrangements 30 shown.

Figure 1 is a longitudinal view of a fished rail joint according to the invention.

Fig. 2 is a horizontal section of Fig. 1 taken through the bolts, the nuts being assumed not 35 tightened.

Fig. 3 is a view similar to Fig. 2 in which the fishing nuts are assumed to have been screwed home.

Fig. 4 is a sectional view taken on line IV— 40 IV of Fig. 1.

Fig. 5 is a sectional view taken on line V—V of Figs. 1 and 2 before the bolt passing through the hole 13 is tightened.

Fig. 6 is a view similar to Fig. 5 showing the 45 bolt tightened.

Fig. 7 is a sectional view taken on line VII—VII of Fig. 1.

Figs. 8 and 9 are, respectively, an elevation and a plan of a modified construction of fish-plate 50 according to the invention.

The rails 1 and 2 are joined by two fishplates 3 and 4 arranged at either side of the rail. These fishplates are constructed so as to support the ends of the rails by their central or active 55

parts 5 resting on bearings or seats on a length corresponding to that where the wear generally takes place. At either side of this active part, 5 are arranged elastic arms 6 and 7 having their ends 8 and 9 resting on the rail. The fishplate is constructed in such a manner that at rest, that is to say when the arms are not acted upon by the bolts which pass through them, they are held away from the rails (Figs. 2 and 5). When 10 the bolt placed in the hole 13 is screwed home, the elastic arm 7 will be elastically bent and brought nearer to the rail, without however reaching it (Figs. 3 and 6). The same applies to the arm 6 when the bolt of the hole 12 is 15 tightened.

The movement of the elastic arms 6 and 7 toward the rail is permitted, due to the fact that these elements or intermediate portions do not have any part thereof in contact with the web 20 of the rail nor with the fish-plate bearing surfaces. On the contrary, the central portion 5 and the end portions 8 and 9 cannot, except in the case of wear, be moved toward the rail, since these parts are in contact with the inclined 25 faces of the head and the foot of the rail which afford bearing surfaces for the fish-plate.

The result of the bending of the elastic arms of the fish-plates is that the central parts 5 are constantly forced to come nearer to the web of 30 the rail and to take up automatically any wear that might have been caused between the fish-plates and the fishplate bearings or seats on the rails.

As regards taking up the play, there are two 35 cases to be considered: In the first of these cases the wear is such that it is taken up by the simple straightening of the elastic arms. In the second place, the wear is greater at the ends of the heads of the rails than at any other point. 40 In order to take up this wear, the central or active part 5 of the fishplate 3 for instance would have to come nearer to the heads of the rails by rising on the inclined plane of the feet or flanges of the rails 2 and 3, to an extent greater than that of the ends 8 and 9. The arms 45 6 and 7 would have therefore to undergo vertical deformation to the extent required for the purpose, and they can undergo such deformation owing to the fact that their strength in this plane is less than that of the central part.

It will be understood that after the fishplates have been used for a certain time, it may be 50 advisable to tighten again the fishbolts and more particularly the bolts of the active or central part. The elastic arms will not offer an excessive resistance to such renewed tightening since they are deformable.

As regards the bolt holes, it must be pointed out that the holes 12—15 of the fishplates are 60 smaller than the holes 10 and 11 whilst in the rails they are all equal to the largest ones. This arrangement has a two-fold purpose: To reduce to the least possible extent the weakening of the arms and of their bearings by the drilling of the holes which they comprise, and further to enable the bolts 12—15 to move in the rails to the amount required by the working 65 of the elastic arms.

For the purpose of facilitating the vertical movement of the fishplates, the holes 12 to 15 are elongated as visible in Fig. 7.

The method of manufacturing fishplates complying with the conditions hereinbefore set forth, may vary in several ways:—

(a) They may be manufactured in the ordinary way and thereupon the arms formed by removing by means of a tool the desired quantity of material. The fishplate would then have 10 the appearance shown diagrammatically in Figure 1, that is to say the height of the arms would be smaller than that of their bearings and than that of the central part (see Figs. 1, 5 and 6).

(b) The fishplate may be stamped out in dies 15 directly to the above shape.

(c) By pressing out: Force away the intermediate parts 6 and 7 to a sufficient distance from the plane which connects the ends 3, 4 and the central part 1 of the fish-plate, so that when 20 the ends and the central part are in contact with the bearing surfaces of the rails, said intermediate parts are not able to come in contact with the bearing surfaces (see Figs. 8 and 9).

What I claim is:

1. In a rail joint, a fish-plate for joining the ends of two rails together, comprising a central portion adapted to engage only bearing surfaces formed on the inclined portions of the head and the foot of the rails to be joined, said 30 central portion bearing on a length of each of the rails corresponding to that portion usually subjected to wear, the extremities of the fish-plate being firmly joined to the rails and the intermediate portions of the fish-plate between 35 the central portion and the extremities thereof being adapted to remain spaced from the fish-plate bearing surfaces and the webs of the rails, and fish-bolts positioned near the middle of the intermediate portions of the fish-plate for pressing the central portion of the fish-plate onto the bearing surface provided on the rails, the said intermediate portions having a weak horizontal rigidity in order to permit the easy bending of said portions by the tightening of the said 40 fish-bolts.

2. In a rail joint, a fish-plate for joining the ends of two rails together, comprising a central portion adapted to engage only bearing surfaces formed on the inclined portions of the head and the foot of the rails to be joined, said 50 central portion bearing on a length of each of the rails corresponding to that portion usually subjected to wear, the extremities of the fish-plate being firmly joined to the rails and the intermediate portions of the fish-plate between 55 the central portion and the extremities thereof being adapted to remain spaced from the fish-plate bearing surfaces and the webs of the rails, and fish-bolts positioned near the middle of the intermediate portions of the fish-plate for pressing the central portion of the fish-plate onto the bearing surface provided on the rails, the said intermediate portions having a rectangular cross-section of small breadth.

NORBERT VRYENS.
